TREATMENT OF OILS.

Application filed May 5, 1915, Serial No. 26,110. Renewed October 17, 1922. Serial No. 595,167.

This invention relates to the treatment of oils; and it comprises a process of treating petroleum oils wherein a body of petroleum material of any nature is heated to a high 5 temperature until a condition of equilibrium among and between the various hydrocarbons therein is established and wherein fresh petroleum material is supplied to said body more or less continuously and at a rate 10 insufficient to disturb substantially the equilibrium relations in said body, one or more of the products of the equilibrium being withdrawn in a similar manner; as by heating a pool or body of high boiling oils, such 15 as crude oil, gas oil, etc., in a roomy chamber, the capacity of such chamber being more than twice the volume of oil (calculated on the volume of cold oil) maintained there- 20 within, till an equilibrium is established between liquids, vapors and gases therein, and during the maintenance of such equilibrium feeding in fresh oil and withdrawing one or more of the products of equilibrium in the liquid state; as by continuously removing 25 liquid gasoline or kerosene or both or equilibrated oil, the feed of fresh oil and the withdrawal of liquid equilibrium products being at such a rate as not materially to dis- 30 turb the prevailing equilibrium within such chamber; all as more fully hereinafter set forth and as claimed.

The production of low boiling oils from high boiling oils by heating such high boiling oils, with or without pressure, is a very old thing in the art; being the operation which is ordinarily known as cracking. Sometimes the oil to be cracked is maintained in a still; sometimes it is run through a hot tube; and many other variations of the high temperature idea are known. But in all, the operation is more or less a distilling operation; the effort is to withdraw the low boiling products from the zone of high heat as fast as they are formed. The low boiling 40 products formed by these cracking operations are of low grade, being largely unsaturated. In a cracking still operating at the ordinary pressure the temperature is usually above 600° F. while the end boiling point 45 of commercial gasoline is about 350° F. Under these conditions the gasoline can of course remain in the liquid undergoing cracking only momentarily and it is evap- 50 orated and removed away substantially as fast as it forms therein. Such as is formed 55 in the vapors is withdrawn with the vapors. It has no opportunity to enter into equilibrium reactions with the liquid or the vapors. Commercial unsaturated gasoline produced by so heating gas oil or oil residues, 60 with or without pressure, forms what is known as cracked gasoline; it is a low grade material, being colored, or tending to assume color, having an offensive odor, sooting in 65 the gas engine, etc. I attribute the formation of unsaturated products, which is the result of all cracking operations, to the fact that the first products of the breaking down of oil are largely ethylenic groups and in 70 the ordinary operation the products are withdrawn from the zone of heat so rapidly that not sufficient time is afforded for further rearrangement with saturation.

I have found that the action of heat and pressure upon oils does not, as is usually 75 presumed, go only one way; it does not merely result in the formation of breaking-down products. On the contrary, I have found that under proper conditions an equilibrium appears in which breaking down and 80 reconstruction actions go forward until a certain balance obtains between the concentration or amount of the gases, of the low boiling oils, and of the high boiling oils in the space afforded for action. Being a true 85 equilibrium it can be approached from either side; that is, I can heat a heavy oil under proper definite conditions until equilibrium is obtained and produce gases together with what I may call a synthetic crude oil; an 90 oil much resembling natural crude petroleum, and containing a definite amount of low boiling hydrocarbons like gasoline. A definite amount of gas is also produced. On the other hand, I can produce this same equi- 95 librium and make the same types of synthetic crude oil by approach from the other side; that is, by heating light oils, or even hydrocarbon gases, under suitable heavy pressure and at a high temperature. I have, 100 for example, so converted propane and other permanent gases into equilibrium mixtures containing high boiling hydrocarbons, some of these hydrocarbons boiling as high as lubricating oil. Kerosene and gasoline may be 105 converted into oily mixtures containing lu-

bricating oil with production of a certain proportion of gases.

As stated, I regard this operation as resulting in the production of a true equilibrium; an equilibrium which exists between paraffin, high boiling oils like lubricating oil, intermediate oils like gas oil, kerosene, gasoline and gases. Being a true equilibrium if one of the products of equilibrium is removed such a product tends to reform at the expense of the other bodies which, together, are in equilibrium. That is, if I treat crude oil or gas oil or any heavy oil under proper conditions of volume and expansion or vapor space, temperature and pressure, an equilibrium is produced in which there will be, with one ratio of expansion chamber to liquid material, quite constantly about 16 per cent of gasoline.

But if during this heating and equilibrium making operation, I have continuous removal of a relatively small amount of gasoline, more gasoline is formed. The gasoline made under equilibrium conditions I find to be saturated and good, being wholly unlike the "cracked gasolines". Its removal tends to disturb the equilibrium and more and more gasoline tends to form as it is removed.

In another application Serial No. 800,323, filed Nov. 11, 1913, whereof the present application is in part a continuation, I have described and claimed broadly methods of making synthetic crude oils containing gasoline, from various oils.

As there pointed out, the equilibrium obtained when a high boiling oil is heated in a closed container without permitting escape of products of reaction depends upon the ratio of the volume of the original liquid and the capacity of the container. Whatever the ratio between the volume of oil and what may be termed the expansion space (the space not occupied by the cold oil), there will always be obtained a material like crude oil. But the character of this oil, the equilibrium which obtains in it, will depend very largely upon this ratio. For example in heating a gas oil in a chamber with an expansion space 10 times that of the volume of oil used only 79 per cent of liquid oil is recovered; but the gasoline contained will be 26 per cent of the original oil. On the other hand with three times as much oil in the same vessel (giving an expansion space having an 8:3 ratio of the liquid space), the amount of liquid oil recovered is 96 per cent but it only contains 13 per cent gasoline. Filling the chamber half full the recovery is 99 per cent but the yield of gasoline is only 5.5 per cent. The best ratio for the production of gasoline from heavy oil in operating in this manner is to have an expansion space between five times and two times the volume of heavy oil treated.

To produce the equilibrium in the case of

a heavy oil I find that a momentary heating so that a gage pressure of 800 pounds is produced suffices. The same results are obtained, more slowly by heating to a gage pressure of 600 pounds. Where light oils or gases are treated, the gage pressure maintained cannot of course be relied upon but I find that in this case heating to a temperature of 400° to 600° C. produces the same result. That is the equilibrium obtains either at an 800 pound pressure (which corresponds to 400° or 500° C. in the case of heavy oil) or a temperature of 500° C. with any oil. Where it can be used the gage pressure is the most convenient index.

Gage pressures up to 2000 pounds have been obtained but the action is not substantially different from that obtained at 800 pounds. The pressures and temperatures required for the equilibrium are, as seen, rather high but I find that the same results can be obtained at lower temperatures and pressures by using an equilibrium accelerating catalyst in the oil. For the sake of distribution through the oil it is best to have this catalyst in a colloidal condition. Colloidal metals, such as nickel produced by electrical disintegration, and colloidal carbon are good catalysts for this purpose. Colloidal graphite of a commercial type is a particularly good catalyst. With the aid of these catalysts an equilibrium can be obtained at pressures as low as 400 or 500 pounds in using a heavy oil.

After equilibrium is obtained, the reaction mixture can be cooled to the ordinary temperature and will then generally show a gage pressure of about 120 pounds, this being due to permanent gases formed.

As to the reason for the existence of these relations between volume of oil and expansion space, I am not certain and content myself with noting observed results. It is my opinion however that the necessity for these ratios depends in some way upon producing a particular concentration of the gas and vapor molecules in the liquid and in the vapor space. That is, presuming methane to be produced, and it is usually one of the products, under ordinary pressures it will dissolve in the liquid to a certain limited extent at any particular temperature; but at very high pressures its solubility in the liquid is enhanced. On the other hand, at the high temperature employed much of the oily products tends to go into the vapor formed; to expand into the expansion chamber. And it may be that under the conditions I employ these liquids reach a critical point. At all events the equilibrium I desire is produced under the conditions recited.

Where, as in the present embodiment of my process, the operation is more or less continuous and the products of reaction remain in the reaction chamber in large part,

the volume ratios are not so fixed in their nature since after an equilibrium is established differences in the amount of feed and of withdrawal do not alter conditions greatly.

5 That is, if a body of cold oil be placed in a chamber and heated up to equilibrium pressure of 800 pounds, certain ratios between chamber capacity and oil volume must obtain to produce certain results. But

10 if the chamber be full of hot, compressed gases, vapors and liquids from a preceding operation then a minor withdrawal of liquid products or addition of new oil does not greatly change the conditions within

15 the chamber; that is, the body of oil maintained under heat is, so to speak, a "dominant pool," its mass being relatively so great that a minor addition and a minor abstraction do not materially affect the equilibrium conditions within the chamber.

20 For example, if a gallon of heavy oil be placed in a 100 gallon chamber and heated up gradually the volatile products of reaction (light oils and gases) would escape into the chamber leaving the oil nearly free of the same and before the 600 or 800 pounds pressure is established, the oil will have cracked down or even coked. But if the

25 chamber be full of gases and vapors under high pressure and temperature, the volume of oil introduced into it becomes less important. Under these conditions, the volatile equilibrium products do not escape from the oil to such an extent.

30 Nevertheless, in the present process I prefer to maintain the volume of oil around 3/11ths of the volume of the treatment chamber; though as stated rather wide variations are permissible once the equilibrium conditions are established.

35 In the production of saturated hydrocarbons by breaking down heavy hydrocarbons into light hydrocarbons either by cracking or my equilibrium process there must be either an addition of hydrogen or a deposition of carbon. Both results obtain in producing the described equilibrium. It is however desirable to restrain the production of hydrogen and also that of permanent gases. As these permanent gases contain very much more hydrogen than the oil from which they are produced it is obvious that in so far as they are formed their production is a waste, not only because of the amount of oil taken to form them, but also because their production represents a deposition of carbon.

40 I have found in operating with the described process that I can obtain low boiling oils from heavy oils with very much more economy if I restrict the escape of permanent gases to the lowest possible amount. Some escape of permanent gases from the system is advantageous possibly for the reason that some methane and hydrogen are

always produced and these gases are but little reactive; they tend to go into the equilibrium more sluggishly than the other products of the equilibrium forming reaction. They do however have some tendency 70 to take part in the equilibrium. Presence of methane and hydrogen is important as aiding in preventing formation of more methane and hydrogen; they exercise so to speak a restraining influence. But an excess of either while it will disappear in time, disappears slowly; it does not exercise the active influence in equilibrium that the other products of reaction do.

45 In the present invention therefore I heat 80 an oil, which for the present purposes may be a crude oil, a distillation residuum, a distillate such as gas oil, or any other heavy oil, under conditions which will allow me to produce either the described 800 pounds 85 pressure or a temperature of 400° or 500°. For the sake of a name the various products of petroleum nature or made from petroleum may be called petroleum materials. By using a certain amount of colloidal graphite or other catalyst in the oil under treatment, I can reduce the temperature necessary to about 350° C. or the pressure to about 650 pounds. Having produced an equilibrium, I slowly remove one 90 of the products of the equilibrium, say the gasoline, without allowing any substantial escape of other products; that is, of the gases produced. Obviously if the equilibrium has gone on to the production of the maximum amount of gasoline which can exist, if this gasoline be slowly extracted new gasoline will continuously form in the effort to reinstate the equilibrium. As previously stated, the equilibrium which obtains 95 is one between all the components of the mixture being treated; and I regard this as probably true as regards each individual hydrocarbon as well as regards the mixtures which we term gasoline, kerosene, etc. I 100 do not allow the gases to escape to any substantial extent; that is I vent off merely enough gas to relieve undue pressures; pressures above, say, my 800 pounds.

105 The removal of the gasoline should be at 115 a rate less than the equilibrium forming rate since otherwise I would obtain, as in the ordinary operation, unsaturated gasoline. It is my object to obtain in this invention a gasoline which is saturated and of high commercial grade, needing no sulfuric acid, or very little, for refining.

110 An advantageous way of abstracting the gasoline is to perform the reaction in a vessel which is locally heated to a high temperature and has a cooler continuation. The gases as formed will bank up in the cooler continuation maintaining the pressure at the desired point while equilibrium tends to obtain in the heated portion of the vessel. So 120 130

to speak the gases and the vapors in the cooler portion of the vessel are merely a gas piston in this action. In the cooler portion of the vessel I arrange cooling devices which will tend to condense out the gasoline and this liquid gasoline I allow to escape as it is condensed, allowing it to pass a loaded valve of some type. In so removing liquid gasoline no wasteful escape of the equilibrium vapors is permitted though from time to time a little gas may be vented off as the concentration of the slowly equilibrizing gases (methane and hydrogen) tends to increase giving an attendant undue increase of gage pressure. As to the frequency with which this venting is required, it depends mainly on the speed of operation since these gases do not refuse to come to equilibrium but are merely slow in equilibrizing.

20 The gasoline produced is clean and sweet, requiring but little if any treatment with acid, being saturated in its nature, where equilibrium obtains in the reaction chamber and the withdrawal of gasoline is small as compared with the volume of oil under treatment. The products when they come into equilibrium appear to be saturated bodies. Where there is no addition of hydrogen from an outside source production of equilibrium is of course attended with a deposition of carbon which also goes into equilibrium with the other materials present. But this carbon under these conditions is deposited as a soft or granular form and does not bake on the heating elements. It may be readily withdrawn with residual oil or liquid products.

In lieu of withdrawing merely the gasoline from the zone of equilibrium, I may also withdraw another product, as for example kerosene. In so doing I may provide two cooler zones of different temperatures in the vessel and provide means for withdrawing liquid from each. If one of these zones is maintained at a temperature between 250° C. and 200° C. while another beyond it is maintained below say 100° C., the first will deliver kerosene while the second will deliver gasoline. The particular temperature at which a particular product condenses however of course depends in great measure upon the pressure. The temperatures given are at 800 pounds pressure.

Or I may withdraw the whole liquid product of the action as an equilibrated liquid or a "synthetic" crude oil, the withdrawal being proportional to the introduction of fresh oil and the amount of addition and withdrawal being small as regards the body or pool of oil within the equilibrium chamber. The point of withdrawal of equilibrated liquid from the body of liquid in the apparatus should be remote from the point of introduction of fresh liquid. In making synthetic oil continuously a tubular vessel is de-

sirable for this reason. With a horizontal or inclined tubular vessel, the oil may be, so to speak, equilibrated in transit.

In the accompanying illustrations, I have shown, more or less diagrammatically, apparatus suitable for the described purposes. In this showing Figure 1 is a vertical section of an equilibrium vessel having a cooler continuation or column adapted for the withdrawal of one or more liquid products of equilibrium; Figure 2 is a similar view of an apparatus adapted to withdraw equilibrated oil continuously; Figure 3 is a view partly in vertical section and partly in elevation of a tubular apparatus for the same purpose, and may be regarded as a detail of Figure 4; and Figure 4 is a view partly in section and partly in elevation of a complete plant embodying the structure of Figure 3.

In the showing of Figure 1, element 1 is a still body which may be heated in any manner and may be of any convenient structure or form. It is fed with oil through inlet 2. Residual oil may be removed through 3. At its top it has an opening 4 communicating with the chamber-like space in a column or tower 5. As shown, this column is provided with gage 6 and valved outlet 7 for permanent gases. Within the column is shown a series of cooling coils 8 through which a cooling fluid, which may be oil or any other high boiling fluid, is sent in the direction shown by the arrow. As shown there are four of these coils which are meant to be maintained at a temperature decreasing upward. Beneath the top coil is a collector basin 9 having a valved outlet 10.

In the use of this structure a suitable oil is fed into reaction chamber 1 through inlet 2; and in this chamber it is heated so that the gage 6 will show a pressure of about 800 pounds. By using an equilibrium-promoting catalyst in the oil, such as deflocculated graphite, colloidal nickel, etc., the necessary pressure may be somewhat diminished, down to 650 pounds. This pressure, with a corresponding temperature which will be between 400° and 500° C., presuming gas oil to be used, will produce equilibrium in the whole system, an equilibrium between the gases, vapors and high boiling oils. In this equilibrium only the contents of chamber 1 need be considered, since the gases and vapors in column 5 act as a fluid piston; i. e., they simply undergo compression until they reach the pressure of the materials in chamber 1. Chamber 1 should be so charged as to preserve the stated ratio between the liquid in it and the expansion space. The expansion space in 5 need not be considered. It is best that the amount of liquid oil charged into it be in volume about 1/3 the capacity of chamber 1.

The gases and vapors in 5 however do not

act purely as a resisting piston of compressed gas; there is a tendency towards diffusion of vapors upwardly into this column. As these vapors pass upwardly past the various coils, their temperature is lowered and high boiling oils are condensed out and flow backwardly into the reaction chamber or equilibrium vessel. If the second coil from the top be maintained at about 200° C. and the top coil be maintained at, say, 100° C., the vapors on passing such second coil will be very largely gasoline and will be condensed by the top coil, the condensate flowing into basin 9 whence it may be removed from time to time or continuously. By changing the temperature of the top pair of coils somewhat the product will be rich in gasoline and kerosene. Other fractions may be simultaneously produced by providing the other coils with basins and outlets at 10^a and 10^b. From time to time or continuously a portion of the permanent gases may be vented through 7.

As described the operation may be continuous, oil being pumped in through 2 and gasoline being formed in and removed from basin 10.

In the structure of Figure 2 element 20 is a still retort or equilibrium chamber of any desired size and heated in any desirable way. At its top it is provided with oil inlet 21 and gage 22. Within it depends an oil withdrawal pipe 23 continuing to valved outlet pipe 24.

35. In the operation of this structure oil is fed in through 21 and joins the liquid pool 25 in the bottom of the apparatus. As the liquid products of equilibrium collect in 25 they rise above the inlet of 23 and escape through 24. The upper part of the retort is filled with vapors and gases and the lower with liquid oil, both being in equilibrium. Oil being constantly fed in under very high pressure and the reducing valve on 24 being set to somewhat lower pressure, equilibrated liquid oil flows out continuously. Any excess of gases formed also automatically finds outlet in the same way. It is best with this form of apparatus to have the depending tube 23 about 0.75 the length of the retort. This makes a liquid body filling only a quarter of the capacity of the chamber whereas elsewhere I have found the ratio to be better about 3:11. In this case the difference is probably due to the fact that the lighter hydrocarbons are in the vapor space and the oil pool contains only the oils not volatile under the high temperature and pressure prevailing.

60. In the structure of Figure 3 element 30 is a very heavy steel tube which may be heated in any manner as by a lead jacket, flame heat, etc. It is set at a slight angle.

65. At the upper end is inlet tube 31 from which oil may be introduced under pump

pressure; as by the use of a pump adapted to work under 800 to 2000 pounds pressure. The inclination of the tube is only such as will permit a slow flow of oil from the top end to the lower end 32 while permitting the existence of the vapor space above the oil from end to end. The oil in this structure is equilibrated in transit. At the lower end is provided an outlet pipe 33 adapted to maintain the level of liquid oil 34, as shown 75 the pipe 33 having a valve 37. In the operation of this structure fresh oil entering at 31 flows slowly down and is removed at 33. During this passage through the tube it comes into equilibrium with the gases 80 and vapors in the vapor space above the oil. The tube is best about three-elevenths full of liquid oil.

In Figure 4, element 35 is a storage tank, 36 is a high pressure tandem pump, 37 is a reducing valve and 38 a pipe leading from outlet pipe 33 to storage tank 39.

In the operation of Figure 3 the gases formed are also vented with the outflowing liquid through 33, gas and liquid passing 90 out alternately or together. The term "petroleum oil" as used herein includes all analogous oils of mineral origin, such as oils derived from the distillation of shale and the like.

95. What I claim is:—

1. The process of converting petroleum oils which comprises establishing and maintaining a body of petroleum oil and vapors therefrom under such heat and pressure as 100 will produce equilibrium in such body and during the maintenance of such equilibrium slowly withdrawing the liquid products of equilibrium and slowly adding fresh oil.

2. The process of converting petroleum oils which comprises establishing and maintaining a body of petroleum oil and vapors therefrom in the presence of a catalyst and under such heat and pressure as will produce equilibrium in such body and during 110 maintenance of such equilibrium slowly withdrawing liquid products of equilibrium and slowly adding fresh oil.

3. The process of converting petroleum oils which comprises establishing and maintaining a body of oil in contact with its own vapors and under such heat and pressure as will produce equilibrium between such vapors and such oil, and during such maintenance slowly withdrawing converted oil 120 from one point in such body and slowly adding fresh oil to another point in such body at a rate insufficient to disturb materially the traveling equilibrium.

4. The process of converting petroleum 125 oils which comprises establishing and maintaining a body of oil as a long column in contact with its own vapors under such heat and pressure as will produce equilibrium therebetween and during such main- 130

tenance slowly feeding fresh oil to one end of said column and slowly withdrawing liquid from the other at a rate insufficient to disturb materially the traveling equilibrium.

5. The process of converting high boiling petroleum oils which comprises establishing and maintaining a body of such oil in a roomy chamber at a heat and pressure which will produce equilibrium between the oil and its vapors and continuously supplying fresh petroleum material and withdrawing liquid products of equilibrium, such supply and withdrawal being at a rate insufficient to disturb the equilibrium prevailing in such body.

6. The process of converting high boiling petroleum oils which comprises establishing and maintaining a body of such oil in a roomy chamber at a heat and pressure which will produce equilibrium between the oil and its vapors and continuously supplying fresh petroleum material and withdrawing liquid products of equilibrium, such supply and withdrawal being at a rate insufficient to disturb the equilibrium prevailing in such body, the volume of said roomy chamber being less than ten times the volume of oil therein and more than twice as great.

7. The process of converting heavy petroleum oils substantially free from light oils into a product containing light oils which comprises heating such a heavy oil in a roomy chamber under a heat and pressure producing equilibrium conditions therein and during such heating slowly feeding fresh oil into said chamber and slowly withdrawing equilibrated liquid products therefrom at a rate insufficient to disturb materially the traveling equilibrium.

8. The process of producing an equilibrated petroleum oil containing gasoline from a heavy petroleum oil substantially free of gasoline which comprises establishing a relatively shallow layer of oil in a horizontal tubular chamber, heating such oil until a pressure of 600 pounds or higher is attained, maintaining the temperature at this point and during such maintenance slowly withdrawing liquid oil from one end of said chamber and slowly supplying new oil to the other end of said chamber.

9. The process of treating petroleum materials which comprises heating a body of such material to a high temperature under high pressure and in the presence of vapors derived from the said material until an equilibrium obtains, maintaining said body of material at such heat and pressure as to substantially maintain such equilibrium and during the maintenance of the equilibrium slowly abstracting from the reaction zone liquid products of such equilibrium.

10. The process of converting petroleum oils which comprises establishing and main-

taining a body of petroleum oil, in contact with vapors thereof, under such heat and pressure as will produce equilibrium between said oil and said vapors, and during the maintenance of such equilibrium slowly withdrawing products of such equilibrium and slowly adding fresh oil.

11. The process of converting high boiling petroleum oils which comprises establishing and maintaining a body of such oil in a roomy chamber at a heat and pressure which will produce equilibrium between the oil and its vapors, continuously supplying fresh petroleum material, establishing a cooling zone of predetermined condensing temperature and withdrawing condensed liquid from the said condensing zone, the said supply and withdrawal being at a rate insufficient to disturb the equilibrium prevailing in the said body.

12. The process of converting high boiling petroleum oil which comprises establishing and maintaining a body of such oil in a roomy chamber at a heat and pressure which will produce equilibrium between the oil and its vapors, continuously supplying fresh petroleum material, establishing a plurality of condensing zones of different predetermined temperatures and withdrawing liquid condensation products from at least one of the said zones, the supply and withdrawal of material being at a rate insufficient to disturb the equilibrium prevailing in such body.

13. The process of converting petroleum materials, which comprises heating a body of the material to a vaporizing temperature in excess of 350° C. while under pressure sufficient to retain at least some of the constituents in liquid state in contact with vapors then maintaining said liquid and vapors at such temperature and pressure as to maintain an equilibrium of constituent hydrocarbons, and abstracting from the reaction zone portions of products while supplying new material.

14. The process of converting petroleum materials, which comprises subjecting a body of the material to a vaporizing temperature in excess of 350° C. while under a pressure sufficient to retain at least some of the constituents in liquid state in contact with vapors, and maintaining an equilibrium of constituent hydrocarbons, while abstracting portions of the products and supplying fresh material.

15. The process of converting petroleum materials, which comprises heating a body of the material to a vaporizing temperature in excess of 350° C. while under a pressure sufficient to retain at least some of the constituents in liquid state in contact with vapors and maintaining all constituents under such temperature and pressure as will produce equilibrium in the constituent hydrocarbons, and continuously withdrawing

products of equilibrium and supplying fresh petroleum material, such withdrawal and supply being at a rate insufficient to disturb the conversion.

5 16. The process of converting petroleum materials, which comprises heating a body of the material to a vaporizing temperature in excess of 350° C. while under a pressure sufficient to retain at least some of the con-
10 stituents in liquid state in contact with va-

pors, and maintaining all constituents under such temperature and pressure as will produce equilibrium in the constituent hydrocarbons, and simultaneously withdrawing products of equilibrium and supplying 15 fresh petroleum material.

In testimony whereof, I affix my signature.

WALTER O. SNELLING.
